UNITED STATES PATENT OFFICE

CHESTER M. MACCHESNEY, OF CHICAGO, ILLINOIS, ASSIGNOR TO ACME STEEL COMPANY,
OF CHICAGO, ILLINOIS, A CORPORATION OF ILLINOIS

BUTTER TUB

Application filed April 1, 1929. Serial No. 351,478.

This invention relates to improvements in butter tubs or other containers and its purpose is to provide an improved hoop construction whereby the parts of the tub are reinforced and maintained in assembled relation. The principal object of the invention is to provide an improved butter tub comprising one or more improved hoops by which the staves of the tub are maintained in assembled 5 relation with respect to the bottom wall without the use of nails or the like for securing the hoops in position on the tub. A further object of the invention is to provide an improved bottom hoop for a butter tub or other 10 container which will retain itself in place without nailing and which will permit a plurality of tubs to be nested one within the other without danger of the hoops being withdrawn from the tubs when the tubs are 15 pulled apart. Still another object of the invention is to provide a butter tub having a bottom hoop provided with an inwardly directed bead engaging a recess in the tub in combination with one or more upper hoops 20 having outwardly directed beads adapted to engage the wall of an outer tub when a plurality of tubs are nested one within the other. Another object of the invention is to provide a tub having a bottom hoop provided with a 25 bead or flange engaging a recess in the tub for maintaining the hoop in position thereon. 30 Butter tubs are commonly made of wood, such as spruce wood or the like, and in order to prevent contamination of the butter or 35 other contents of the tub, it is important to avoid driving nails through the relatively thin staves of which the walls of the tubs are formed. The upwardly extending and outwardly flared staves are engaged adjacent 40 their lower ends by the bottom wall of the tub and these parts are ordinarily secured in assembled relation by means of a plurality of surrounding hoops which are preferably formed of sheet metal. In order to avoid the 45 driving of nails into the staves of the tub, the sheet metal hoops are commonly placed thereon with a drive fit and this frictional engagement is depended upon to prevent removal of the hoops. The uppermost hoops 50 which surround the tub do not require to be

placed in any definite location and may be driven upwardly on the flaring tub until they have such a tight engagement therewith that they cannot readily be removed, but the lower hoop must surround the lower ends of the staves to maintain them in tight engagement with the lower wall of the tub and thus the lower hoop must occupy a more or less definite position which precludes its being driven on until a predetermined frictional engagement is obtained. These limitations sometimes give rise to difficulties when a number of tubs are nested one within the other for shipment which is the preferable 55 arrangement in order to save shipping space within railway cars, because, when the tubs are subsequently separated from each other, there is a tendency for the lower hoops to be pulled off of the bottoms of the tubs. The fact that there may be some variation in the circumference of the tubs and a variation in the circumference of the hoops increases this 60 danger because of the fact that all of the hoops must occupy substantially the same relative position with respect to the bottoms of the tubs. These difficulties are overcome 65 in the present invention by providing a bottom hoop which is automatically retained in place on the tub without nailing and which is employed in combination with other hoops of such construction that the bottom hoop does not come into contact with adjacent tubs when the tubs are nested one within the other. Other features and advantages of the 70 invention will appear more fully hereinafter. 75

The nature of the invention will be understood from the following specification taken with the accompanying drawing in which one embodiment is illustrated. 85

In the drawing, Figure 1 shows a perspective view of a butter tub equipped with the improved hoop of the present invention;

Fig. 2 shows a partial vertical section through one side portion of the tub illustrated in Fig. 1, taken on the line 2-2 of Fig. 1; 90

Fig. 3 shows a partial side elevation, on an enlarged scale, of a portion of the lower hoop illustrated in Fig. 1, showing the means for 100

securing the overlapping ends of the hoops together; and

Fig. 4 shows a partial vertical section through a plurality of butter tubs equipped with the hoops in the present invention showing their arrangement when in nested relation to each other.

As illustrated in the drawing, the improved butter tub 10 comprises a plurality of vertical staves 11, formed of wood, which are arranged edge to edge to form an upwardly and outwardly flared wall of circular cross-section within which there is secured the bottom wall 12, also formed of wood which is maintained against vertical displacement by having its outer tapered edge 12^a secured within an annular groove 13 which is formed in the staves 11. The upper portions of the staves 11 are surrounded by hoops 14, formed of sheet metal. These hoops are preferably formed by passing a flat band of sheet metal of suitable width and thickness through dies of the proper form to provide an outwardly rolled cylindrical bead 14^a along the lower edge of each hoop and to provide an outwardly bowed intervening part 14^b which terminates adjacent its upper edge in an outwardly directed annular lip 14^c. The ends of the hoop which are thus formed are secured together, preferably by spot-welding, and the hoops are driven onto the tubs from the bottom with the lips 14^c directed upwardly. The hoops may have an initial upward flare, but even when they are of cylindrical form, the upper edges thereof, which are not reinforced by a bead, are adapted to stretch as the hoop is driven upwardly over the tub so that the hoops 14 are formed to the flare of the tub and are adapted to exert a tight frictional grip thereon when they are driven to their extreme position. The beads 14^a then project outwardly beyond the other portions of the hoops 14 so that when a plurality of tubs are nested one within the other, as shown in Fig. 4, the beads 14^a on an inner tub are the only parts of that tub which engage the wall of the next adjacent outer tub.

Around the lower annular edge of the tub 10, there is located a reinforcing hoop 15 formed preferably of sheet metal and having along its lower edge an inwardly directed cylindrical bead 15^a which occupies a recess 16 formed by turning or otherwise cutting off the lower annular edge of the tub, after the staves have been assembled on the bottom wall 12, to form an inclined annular beveled edge 17. The body portion 15^b of the hoop 15 conforms to the taper of the staves 11 and terminates at its upper end in an inwardly convex and inwardly directed annular projection or half-bead 15^c which is adapted to occupy a recess 18 formed in the annular wall of the tub, preferably at the time of forming the depression 16. The hoop 15 is formed from sheet metal by passing it

through suitable dies to impart the inwardly directed bead formation 15^a to the lower edge thereof and to form the half bead or projection 15^c along the upper edge thereof. The hoop 15 is pressed preferably cylindrical in form so that some stretching thereof is required in order to cause it to conform to the taper of the tub when it is driven thereon. The overlapping ends of the bead 15 are preferably secured together as shown in Fig. 3 by means of spot-welding. For this purpose, the bead 15^a is preferably cut away from each end of the band for a short distance, leaving two projecting tongues 19 extending beyond the ends 20 of the bead which then substantially abut against each other. The overlapping end 19 on the inner side of the hoop 15 is preferably fitted within the end portion of the bead 15^a at the other end of the hoop and the overlapping ends are then secured together by spot-welding as shown at 21. These spot-welds 21 are preferably arranged in two divergent series extending on opposite sides of a central spot-weld 21^a which is located opposite the abutting ends 20 so that there is no danger of weakening the metal adjacent to the point where the abutting ends 20 of the beads are located. The half beads 15^c fit one within the other and two of the welds 21 are preferably located in proximity thereto. The completed hoop 15 is driven onto the tub from the bottom and its diameter is such that the inwardly directed half bead or projection 15^c is adapted to engage the upper portion of the inclined annular surface 17 when the hoop is first brought into engagement with the tub. Further driving of the hoop 15 causes the half bead 15^c to ride over the upper portion of the surface 17 and thence upwardly around the outer surfaces of the staves until it snaps into engagement with the annular depression 18, thereby maintaining the hoop in positive engagement with the staves 11 of the tub.

In Fig. 4 of the drawing there is illustrated the relative arrangement of a plurality of tubs nested one within the other. It will be seen that the outer walls of the tubs are spaced apart by the upper hoops 14 which are preferably so constructed that the beads 14^a thereof only engage the inner surfaces of the staves of the next adjacent outer tub. Inasmuch as the beads 15^a on the bottom hoop 15 of each tub are directed inwardly into the recesses 16, the hoops 15 are maintained entirely out of engagement with the staves of the interfitting tubs so that when the tubs are pulled apart there is no danger of removing the lower hoops of any of the tubs and, due to the fact that the upper hoops 14 may be driven on to secure any desired tightness of fit, these hoops are not loosened or removed by the upward movement of any tub when the tubs are disassembled from nested relation. If, due to distortion of any

of the tubs, the lower hoop of any tub engages the wall of the next adjacent outer tub, the interlocking engagement of the annular projection 15° with the depression 18 5 will prevent the bottom tub from being removed when the tubs are pulled apart.

Although one form of the invention has been shown and described by way of illustration, it will be understood that it may be constructed in various embodiments within the 10 scope of the appended claims.

I claim:

1. The combination with a container formed of non-metallic material and having 15 an annular groove therein, of substantially inextensible metallic reenforcing band having an inwardly extending projection interlocking with said groove and having an inwardly extending annular bead formed 20 thereon, said band having a drive fit on the wall of said container.

2. The combination with a container having an annular recess around its lower edge, of an annular reenforcing band extending 25 around such container and having an inwardly extending bead along its lower edge engaging said recess.

3. The combination with a container having an annular recess around its lower edge 30 and an annular groove spaced above its lower edge, of a reenforcing band having an inwardly directed part engaging said groove and another inwardly extending part engaging said recess.

35 4. The combination with a container formed of a plurality of upwardly flaring non-metallic staves and having a non-metallic bottom wall, of a metallic reenforcing band extending around said container outwardly 40 from said bottom wall, said container resting on the lower ends of said staves having a groove therein on its outer side adjacent said bottom wall, and a projection formed on the said band engaging said groove, said container having an annular beveled recess 45 around its outer lower edge, and a bead formed on said band and extending inwardly therefrom to engage said recess.

50 5. The combination with a non-metallic container having an upwardly and outwardly flared annular wall, of a plurality of metallic reenforcing bands extending around said outer wall above its lower edge, each of said bands having an outwardly extending annular bead formed thereon, said container having 55 an annular recess around its lower edge, and another metallic band extending around said container adjacent its lower edge and having an inwardly directed bead engaging 60 said recess.

6. The combination with a non-metallic container having an upwardly and outwardly flared annular wall, of a plurality of metallic reenforcing bands extending around 65 said outer wall above its lower edge, each of

said bands having an outwardly extending annular bead formed thereon, said container having an annular recess around its lower edge, and another metallic band extending around said container adjacent its lower edge 70 and having an inwardly directed bead engaging said recess, said container having an annular groove therein adjacent the upper edge of said last named band, and an inwardly directed annular half-bead formed on said last named band and engaging said groove. 75

7. The combination with a container having an annular upwardly flared non-metallic wall provided a short distance above the lower end thereof with an annular groove, said container having its lower edge beveled downwardly and inwardly from said outer wall to form a recess, and an annular metallic band driven upwardly onto the lower end of said annular wall, said band having an inwardly projecting annular part around its upper edge sprung into engagement with said annular groove, said band being provided around its lower edge with an annular inwardly extending bead engaging said recess. 80

8. The method of forming a container which consists in providing a vessel having an annular upwardly flared wall of non-metallic material, providing an annular groove in said annular wall a short distance above the lower end thereof, providing an annular recess at the lower edge of said annular wall, and then driving onto said annular wall from the lower end thereof an annular metallic band of cylindrical form provided with an inwardly extending annular projection around its upper edge and with an inwardly extending annular bead around its lower edge, whereby said inwardly extending annular projection on said band snaps into engagement with said annular groove and said annular bead engages said annular recess. 90

9. In combination, a plurality of containers having upwardly flared annular walls nested one within the other, said containers being provided around intermediate portions thereof with annular metallic bands provided with outwardly extending annular beads each of which engages the inner surface of the annular wall of the next adjacent container in said nested relation, each of said containers being provided adjacent its lower end with an annular groove and with an annular recess around its lower edge, and a metallic band on each of said containers having an annular inwardly extending part sprung into engagement with its groove and with an annular inwardly extending bead engaging its recess, whereby said bands around the lower ends of said containers are out of contact with the inner surfaces of the walls of the respective next adjacent container. 100

In testimony whereof, I have subscribed my name.

CHESTER M. MACCHESNEY.
